CLAIM

The ornamental design for a skin tool, as shown and described.

DESCRIPTION

FIG. 1 is a front isometric view of a skin tool showing the new design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines illustrate portions of the skin tool that form no part of the claimed design.
